UNITED STATES PATENT OFFICE.

WILLIAM H. WHITE, OF ROANOKE, VIRGINIA, ASSIGNOR, BY MESNE ASSIGNMENTS, TO GRAHAM-WHITE SANDER CORPORATION, OF ROANOKE, VIRGINIA, A CORPORATION OF VIRGINIA.

LOCOMOTIVE SANDER.

Application filed October 15, 1924. Serial No. 743,793.

To all whom it may concern:

Be it known that I, WILLIAM H. WHITE, a citizen of the United States, residing at Roanoke, in the State of Virginia, have 5 invented certain new and useful Improvements in Locomotive Sanders; and I do hereby declare the following to be a full, clear, and exact description of the invention, such as will enable others skilled in 10 the art to which it appertains to make and use the same.

The invention relates to sanders for locomotives and more particularly to automatically operated sanders whose operation 15 is initiated by the operation of at least a portion of the driving mechanism of the locomotive.

To this end, the principal object of the invention, generally stated, is to provide 20 pneumatic or fluid pressure sanding operating means arranged in conjunction with a locomotive in which at least a portion of the driving mechanism is adapted to be brought into operation by fluid pressure, 25 the arrangement being such that the sander is brought into operation simultaneously with the operation of the fluid pressure means controlling the portion of the locomotive driving mechanism.

Still another object of the invention is to provide a pneumatically operated sanding mechanism adapted for use with a so-called booster locomotive, the arrangement being 30 such that the sander is adapted to be brought into operation by the operation of the fluid pressure control of the booster.

A still further object of the invention is to provide in a device of the character above described, a pneumatically operated valve 40 which is operatively connected to the booster sander and interposed in the booster controlling line and so arranged that at the option of the engineer the sander may be operated either prior to, simultaneously 45 with, or during the operation of the booster.

To these and other ends the invention comprises the various elements and combinations of elements as hereinafter set forth, the novel features thereof being pointed out 50 in the claims.

In the drawings:

Figure 1 is a diagrammatic view showing

a locomotive equipped with booster operated trailer wheels showing the sanding mechanism for the locomotive wheels and 55 additional sanding mechanism for the booster wheels, and illustrating also the position and connection between the sander operating valve and the booster controlling mechanism.

Figure 2 is a view in vertical cross section 60 of a pneumatically operated sander controlling valve.

Figure 3 is a side elevation of the same.

Figures 4 and 5 are respectively cross sections on the lines 4-4 and 5-5 of Figure 65 2, the direction of view being indicated by the arrows adjacent the ends of said section lines.

Throughout the specification and drawings like parts are designated by like reference characters.

Before describing the particular embodiment of the invention here illustrated in detail, it is pointed out that while I have shown the invention as applied to a booster equipped locomotive of a well known type, the invention is of broader aspect than here illustrated and that it is equally well adapted for use in connection with locomotives in which either a portion or the entire driving mechanism is controlled by fluid pressure means, or in other words, the locomotive in which the throttle control is pneumatically operated rather than manually is within the broad aspect of the invention. 75 In the construction here illustrated the booster mechanism comprises a steam engine carried by the trailer wheels of the locomotive and adapted to be operatively connected to the trailer wheels by a fluid pressure cylinder, the said cylinder operating 80 through appropriate means to connect and disconnect the trailer axle to the booster engine by means of intermeshing gears, the said gears consisting of a train operated by 85 the engine, which train of gears is thrown into or out of mesh, as the case may be, with the gear wheel carried by the trailer axle through the fluid pressure cylinder above mentioned.

Referring now to the drawings, the numeral 1 designates a locomotive equipped with a sand dome 2 and a plurality of sanding casings 3-3 by which the amount of

sand flowing to the track for the locomotive driving wheels 4 is controlled. It is of course understood that the sanding casings 3 are operated at will by the engineer or operator from a valve casing 5 within the cab, the operation of which is controlled by a suitable handle or operating lever 6. It is of course understood that similar sanding casings are on the opposite side of the locomotive and are controlled in unison by the engineer or operator. At a point adjacent the sand dome 2 there is applied an additional sanding casing 7, the discharge end of which is connected to a pipe 8 and leads through a suitable flexible connection 9 to a point immediately in front of the trailer wheels 10 of the locomotive, the said trailer wheels being adapted to be connected as hereinbefore described, to the booster engine diagrammatically illustrated and indicated by the reference character 11. It is also to be understood that a similar sander casing pipe and flexible connection are on the opposite side of the locomotive and positioned so as to deliver sand in front of the opposite trailer wheel.

The operating mechanism for the sander casings 7 will now be described. The numeral 12 indicates a fluid pressure supply pipe through which fluid pressure under the control of the operator is adapted to connect the booster engine 11 to the trailer axle 13. Leading from the pipe 12 there is a pipe 14 and at a suitable point on said pipe and in convenient reach of the engineer or operator is a two-way valve and operating handle 15. The pipe 14 passes beyond the valve 15 and is adapted to be connected to a pipe 16 which is also provided with a suitable valve and operating handle 17, the purpose and object of which will hereinafter be described, the said pipe 16 being connected on one side of the pipe 14 with a valve casing 18. The casing 18 is provided with a plurality of communicating cylindrical chambers 19, 20 and 21. Housed within the chamber 19 is a piston 22 having a stem 23 extending downwardly therefrom and engaging the upper face of a piston 24 which is housed within the chamber 20. The piston 24 is likewise provided with a stem 25 which in turn engages a wing valve member 26 which is disposed within the cylinder chamber 21, and interposed between the bottom of the valve member 26 and a closure member 27 is a spring 28. The chamber 20 is provided with a plurality of pairs of openings designated respectively as 29 and 30 which 60 preferably are diametrically opposed and which are connected by means of pipes 31 and 32, respectively, to the sander casings 7. Within the chamber 19 and located above the normal position of the piston 22 is a bleed port 33 and at a convenient point on

the lower end of the said chamber 19 is another bleed port 34.

The operation of the device is as follows: With the two-way valve 15 positioned as indicated in Figure 1, the admission of fluid pressure to the booster actuating mechanism causes an inflow of fluid pressure through the pipes 14 and 16 and from the pipe 16 through the pipe 35 which enters the casing 18 at a point over the top of the piston 22. The pipe 36 which enters the chamber 21 through the opening 37 therein is connected to the same source of fluid pressure as is the pipe 35 but owing to the difference in areas of the piston 22 and the valve member 26, the admission of fluid pressure through the pipe 35 causes a downward movement of the pistons 22 and 24 and the valve member 26, thus admitting fluid pressure from the casing 21 into the casing 20. The fluid passing within the casing 20 is adapted to supply first a cleaning blast of air through the pipes 31 as is well known, before the continued downward movement of the piston 24 blocks off the openings or ports 29 leading to the pipes 31 and consequently further flow of fluid pressure must traverse the pipes 32 and operate the sanding casings 7 and hence supply sand to the trailer wheels 10.

It will therefore be seen from the foregoing description that simultaneously with the operation of the booster actuating mechanism I supply to the trailer wheels a flow of sand provided of course that the valve 15 is in the position shown in Figure 1. The valve 15 may, at any time desired, be actuated so as to close the pipe 14 and prevent the actuation of the sanding mechanism.

It is sometimes desirable, however, to apply sand to the track prior to the actuation of the booster controlling mechanism and I provide means whereby this result may be obtained. The valve mechanism 17 is adapted to control the admission of fluid pressure to the casing 18 should it be desired, as indicated above, to supply sand prior to the actuation of the booster and in this instance the valve 17 is rotated from the position shown in Figure 1 to a position where the handle is at right angles to the pipe 16 whereupon fluid pressure will be admitted to the casing 18 and the operation of the sanding mechanism hereinbefore described will occur. It is to be observed that I have provided means whereby the sanding mechanism for the booster wheels may be operated simultaneously or synchronously with the starting of the booster engine and means whereby the operation of the sanding mechanism may be interrupted without affecting the operation of the booster actuating mechanism and I have also provided means whereby the sanding

mechanism for the booster wheels may be operated independently of the booster actuating mechanism.

Having now described my invention, what I claim as new and desire to secure by Letters-Patent, is:

1. The combination with a locomotive, of fluid pressure means adapted to cause the actuation of a portion of the driving mechanism thereof, a sanding valve mounted on the locomotive, means for connecting said valve to a wheel sander, and means for operatively connecting said sander valve to said fluid pressure actuating means.
2. The combination with a locomotive having certain of the wheels thereof connected to a source of power, of fluid pressure means for controlling the operation of said source of power, a sanding valve connected to said locomotive, means for connecting said valve to a sander for said wheels, and means for operatively connecting said sanding valve to said fluid pressure means.
3. The combination with a locomotive having certain of the wheels thereof connected to a source of power, of fluid pressure means for controlling the operation of said source of power, a sanding valve connected to said locomotive, means for connecting said valve to a sander for said wheels, and means including a fluid actuated valve connected to said fluid pressure means for actuating said sander simultaneously with the actuation of said source of power.
4. The combination with a locomotive having a booster engine and fluid pressure actuating means therefor, of a sanding valve, means for connecting said valve to a sander for said booster wheels, and means for operatively connecting said sander valve to said booster actuating means.
5. The combination with a locomotive having the trailer wheels connected to a booster engine, of fluid pressure means for connecting said wheels to said engine, a sander for said trailer wheels, and means including a fluid actuated valve connected to said fluid pressure means for actuating said sander simultaneously with the power actuation of said trailer wheels.
6. The combination with a booster equipped locomotive, of fluid pressure means for connecting and disconnecting the booster engine and trailer wheels, a sander for said wheels, an actuating valve therefor, a connection between said fluid pressure means and said valve whereby the connection of said engine and trailer wheels causes an actuation of said sander.
7. The combination with a locomotive having a booster engine and fluid pressure

actuating means therefor, of a sander for said booster wheels, a sanding valve connected with the sander, and means for operatively connecting said sander valve to said booster actuating means.

8. The combination with a locomotive having a booster engine equipped with fluid pressure control means, of a sander for the booster wheels, a sanding valve connected with the sander, and means for operatively connecting said valve with the booster control means.

9. The combination with a locomotive having a booster engine for its trailer wheels and having fluid pressure means for actuating the booster, of a sander for the trailer wheels, a sanding valve for operating the sander, and means for operatively connecting the sander valve with the booster actuating means.

10. The combination with a locomotive having trailer wheels equipped with a booster engine and further having fluid pressure control and actuating means for the booster engine, of a sanding valve for the trailer wheels connected with the sander, and means for operatively connecting said valve to said booster actuating means.

11. The combination with a locomotive having a booster and fluid pressure means for throwing the booster into or out of operation, of a sander for the booster wheels, a valve for controlling the operation of the sander, and an operable connection between said fluid pressure means and said valve for effecting simultaneous movement of the sander and booster.

12. The combination with a locomotive having a booster engine for its trailer wheels, of fluid pressure means for controlling the actuation of the booster engine, a sander for the trailer wheels, a controlling valve operatively connected with the sander, means for operatively connecting the valve to the booster actuating means for simultaneous operation therewith, and means for controlling the operation of the valve during or prior to actuation of the booster.

13. The combination with a locomotive having a booster engine for its trailer wheels, of fluid pressure means for throwing the booster into or out of operation, a sander for the trailer wheels, fluid pressure responsive means connected with the sander for actuating the same, and means for operatively connecting said fluid pressure responsive means with said booster actuating means.

In testimony whereof I affix my signature.

WILLIAM H. WHITE,
